UNITED STATES PATENT OFFICE.

ROBERT LIDDELL, OF PUTEAUX, FRANCE, ASSIGNOR TO SOCIETE PARISIENNE DES PRODUITS DE BEAUTE "GANNA WALSKA," OF PANTIN, FRANCE.

DESIGN FOR A BOTTLE.

Application filed October 3, 1927, Serial No. 23,615, and in France June 21, 1927. Term of patent 7 years.

To all whom it may concern:

Be it known that I, ROBERT LIDDELL, a citizen of the French Republic, residing 11 Rue Michelet, Puteaux, in the Department of Seine and Republic of France, have invented a new, original, and ornamental Design for a Bottle, of which the following is a specification, reference being had to the accompanying drawing, forming part thereof.

The figure is an elevational view of a bottle, and of its stopper showing my new design.

I claim:

The ornamental design for a bottle substantially as shown.

ROBERT LIDDELL.
